[57] CLAIM

The ornamental design for a dispensing apparatus for comestibles or similar article, as shown and described.

DESCRIPTION

FIG. 1 is a perspective view of a dispensing apparatus for comestibles or similar article, showing our new design, showing the top, front, and right side thereof; FIG. 2 is a left side elevational view, the side opposite being a mirror image thereof;

FIG. 3 is a rear elevational view thereof;

FIG. 4 is a top plan view thereof;

FIG. 5 is a bottom plan view thereof; and

FIG. 6 is a front elevational view thereof.
